UNITED STATES PATENT OFFICE.

CHARLES M. HIGHSMITH, OF DENVER, COLORADO.

WINDOW-CLEANER.

1,201,183.

Specification of Letters Patent. Patented Oct. 10, 1916.

Application filed May 26, 1916. Serial No. 100,117.

To all whom it may concern:

Be it known that I, CHARLES M. HIGHSMITH, a citizen of the United States, residing at Denver, in the county of Denver and 5 State of Colorado, have invented certain new and useful Improvements in Window-Cleaners; and I do hereby declare the following to be a full, clear, and exact description of the invention, such as will enable others 10 skilled in the art to which it appertains to make and use the same.

This invention relates to windows, and more especially to devices for cleaning the same.

15 The particular object of the invention is the production of a device of this kind for the cleaning of locomotive cab windows, headlights, pilot house windows, and electric and traction car windows with heated air. It permits no water, snow, ice, frost, steam or dust to accumulate or remain on the said windows or headlights, and leaves at all times an unobstructed view through the glass thereof, regardless of weather conditions. 20 This object is attained by means of a device placed through the frame, casing or sash of the glass and directing the flow of heated compressed air against both sides of the glass at the same time, the mechanism of which is illustrated in the accompanying drawings wherein:

Figure 1 is a vertical section through the frame and upper rail of the lookout window in a locomotive cab, pilot house, or street car, giving a side elevation of the attachment. Fig. 2 is an elevation of the interior of a locomotive cab, showing this attachment as applied to the windows therein, and Fig. 3 an elevation from the outside of the 35 front end of a motor car, also showing the attachment applied. Fig. 4 is an elevation of the attachment alone, viewed from the front as seen in Fig. 1. Fig. 5 is a perspective view showing the entire attachment 40 and its connections with the cab and the boiler of a locomotive, and a supplemental cleaner as attached to its headlight. Fig. 6 is a front elevation of the headlight and attachment on an enlarged scale.

50 I have used the numeral 10 to designate a pane of glass mounted within a sash 11 which constitutes the lookout window of a locomotive cab, pilot house, motor car, or the like; and the sash might be mounted 55 to swing or to slide in the window frame 9, or it might be mounted directly within the

front wall 8 of the cab. The attachment is perhaps best seen in Fig. 1 where it is permanently connected with the frame 9, although it is obvious that it might pass 60 through the sash 11. It comprises inner and outer curved pliable pipes 1 and 2 whereof each has its tip 3 directed toward the pane of glass 10 and flattened as best seen in Fig. 4, and each has its other end connected in any suitable manner (as permanently by soft solder or movably by a swivel or otherwise) with the head 6 and the threaded end respectively of a tubular bolt 5, the latter being passed through an 65 opening in the frame or sash and held therein by a nut 7 with suitable washers if desired. The bolt head 6 is cored or bored with a lateral opening communicating with the axial bore through the bolt—both as 70 shown in dotted lines—and an elbow 4 connects this lateral opening with a supply pipe 12 through which hot or warm air under pressure is constantly supplied. This heated compressed air being directed in a flat 75 stream against both sides of the glass at the same time, removes all the water, snow, ice, frost, steam or dust from the window, leaving an unobstructed view through the glass at all times regardless of weather conditions, giving the person in charge of the 80 locomotive, boat or car a clear view of the track ahead and thus avoiding the probability of accidents on account of obstructed windows or lookouts.

90 While any suitable source of supply for the air may be employed, I prefer that shown herein. The air is taken from a reservoir 14 wherein it may be compressed by the air pump of the locomotive or may be 95 under other compression, and is led thence through a coil 15 beneath the shell 21 of the boiler 19 where it is heated by the proximity to the furnace; or it may be that in warm weather the compressed air can be led direct from the reservoir without utilizing the coil. The supply pipe 12 contains a control valve 16 so that the engineer or motorman can cut off or reduce the supply at his pleasure.

100 In Fig. 5 is shown a branch pipe 20 leading from the supply pipe near the coil and having its own control valve 17, and this pipe 20 leads to the headlight 18 and an attachment similar to that shown in Fig. 1 excepting that only the outer pipe 2 is necessary on the glass of the headlight. Here 105 110

its function is the same, and the glass is kept cleaned by a light flow of warm compressed air, or if the valve 17 has been closed and the glass of the headlight has become 5 clouded, it may be cleaned by turning on the air at will.

I consider the use of a pliable pipe especially important, because, even if the nozzles 1 and 2 are not swiveled as suggested 10 above, they may be bent slightly so that the tips 3 can be directed toward the glass 10 at the proper angle. Sometimes the sashes are fixed, but usually they slide. Occasionally they swing, and if in swinging they 15 strike one of the nozzles, the same can be deflected if it is of pliable pipe, or could be turned if it is swiveled in the bolt. Any appropriate form of swivel may be employed, and I do not consider it necessary 20 to show its details.

It will be evident that without departing from the spirit of this invention it may be applied to the windshield of an automobile and the like for keeping the same free of 25 dirt, snow, moisture, etc. In such case, there being no sash, the invention could be mounted upon the frame of the shield or otherwise in any ordinary or well-known manner instead of being placed in or through the 30 sash as described in application to locomotive cab window. Also in such case no inner pipe 1 would be necessary as there is no accumulation of moisture (nor of dirt) upon the inside of a windshield.

35 What I claim is:

1. In a device of the class described, the combination with a bolt passing through a window frame and having a bore through its body and laterally out its head, and 40 means for supplying compressed air to the lateral bore; of curved nozzles each having one end fast in one extremity of said bore and a tip at its other end directed toward the glass of the window.

45 2. In a device of the class described, the

combination with a tubular conduit extending through the frame of a window, and means for supplying compressed air to its interior; of curved nozzles of pliable metal each having one end fixed in one extremity 50 of said conduit and its other end flattened into a tip directed toward the glass of the window.

3. In a cleaner for the window of a locomotive cab, the combination with a conduit through the window frame, and nozzles in its extremities having their tips directed toward the glass of said window; of a source of air supply, a coil therein adjacent the boiler, a pipe leading from the coil to said 60 conduit, and a control valve in said pipe.

4. The combination with the cab windows and headlight of a locomotive, a nozzle having a flattened tip directed obliquely onto the exterior of the headlight glass, a pair of 65 nozzles having flattened tips directed obliquely toward opposite sides of the cab window glass, and a conduit connecting the shanks of these nozzles and passing through the frame of said window; of an air reservoir, a coil connected therewith and standing adjacent the boiler, a pipe leading therefrom and branched, one branch leading to said conduit and the other to the headlight 70 nozzle, and control valves in said branches.

5. In a glass cleaning device of the class described, the combination with a tubular bolt whose ends stand on opposite sides of the glass, and means for supplying compressed air to the bore of such bolt; of two 75 curved nozzles of pliable material each having one end fast in one extremity of said bore and a tip at its other end flattened and adapted to be directed toward the glass.

In testimony whereof I affix my signature 80 in presence of two witnesses.

CHARLES M. HIGHSMITH.
